Inventor,
Emil E. Novotny
By his Attorneys,

Meyers, Cushman & Co.

UNITED STATES PATENT OFFICE.

EMIL E. NOVOTNY, OF RIVERSIDE, ILLINOIS, ASSIGNOR TO J. STOGDELL STOKES, OF MOORESTOWN, NEW JERSEY.

PRINTING-PLATE.

1,377,503.

Specification of Letters Patent. Patented May 10, 1921.

Application filed December 1, 1916. Serial No. 134,323.

To all whom it may concern:

Be it known that I, EMIL E. NOVOTNY, a citizen of the United States and resident of Riverside, in the county of Cook and State 5 of Illinois, have invented certain new and useful Improvements in Printing-Plates, of which the following is a specification.

This invention relates to stereotype plates such as are used in printing and embossing, 10 and particularly in an improved method of making the same.

In the present instance it is my purpose to provide a plate of this character wherein the impression face is formed of a smooth, 15 close-grained, durable material, such as copper, brass or other suitable metal of relatively high melting point which is intimately united with the body of the plate, the latter being composed of the usual soft 20 metal such as a lead alloy having a relatively low melting point.

As is well known to those skilled in the art, ordinary stereotype plates are made either entirely of a soft metal, such for example as an alloy of lead and antimony, or are composed of some such soft metal, coated or faced electrolytically with a very thin film of copper or nickel. Furthermore in the manufacture of such plates it is the 25 common practice to employ a papier-mâché matrix which is made by laying the flong, or matrix forming sheets on the face of the locked type, and beating or rolling the flong against the type to reproduce the type faces, 30 then drying the matrix and subsequently casting the stereotype plate therefrom. Such a plate possesses certain inherent disadvantages among which might be mentioned excessive and objectionable porosity, 35 resulting in granular printing; softness of metal, which is conducive to the rapid wearing of the printing surface of the plate; and finally inability to produce, in printing, sharp clear outlines, thus incurring the loss 40 of details.

The above mentioned objections and others of a similar nature are overcome or eliminated by my plate which possesses the further advantage that it may be made by 45 the exceedingly simple, rapid and economical method herein recited, which obviates the necessity of having recourse to tedious complicated and expensive manufacturing processes.

With the above recited objects and others

of a similar nature in view, my invention consists in the improved plate and in the method of making the same set forth in and falling within the scope of the appended claims.

In the drawings,—

Figure 1 is a cross sectional view taken through a complete plate embodying my invention.

Fig. 2 is a view of a conventional form of 65 press and showing a step in the manufacture of the matrix or mold for the plate.

Fig. 3 is a similar view of a second step in the manufacture of the plate.

In the practice of my invention, the body 70 of type, which is indicated by the numeral 1, is locked in the chase as usual, and is placed on the bed 2 of any preferred or suitable form of press which also includes the platen 3. Such press is herein merely conventionally shown. Upon the face of the type body 1 I superpose a thin wafer-like sheet of malleable, ductile metal as shown at 5, copper, brass or soft steel being preferably employed. I then superpose upon the 80 metal sheet a second sheet shown at 6, and which may be composed entirely of a phenolic condensation product, such as that known as "condensite," or may be in the nature of a composite sheet comprising a 85 facing layer of the phenolic condensation product, and a backing layer of any suitable, inexpensive material, such as paper. This phenolic sheet if desired may have an asbestos filler incorporated therein to increase its 90 heat-resisting qualities.

The phenolic sheet is employed, because this material will insure that the metal sheet 5, will receive accurate, sharply defined impressions from the type faces and rounded 95 non-printing portions, as such phenolic product when in a proper state of plasticity has but a restricted surface flow, while providing a rigid back. This phenolic sheet 6 is preferably heated prior to its application to the metal sheet 5, so as to give it the required plasticity, but in some instances it may be advisable to heat it while in the press. After the metal sheet and the phenolic sheet have been assembled relative 105 to the type body, as described, the upper platen 3, of the press, is lowered toward the bed 2 and into contact with the phenolic sheet in a manner and under sufficient pressure to cause the type faces to be embedded 110

in the metal sheet 5, preferably to a predetermined or definite depth so that while the lower or type-contacting face of the sheet 5 will have type-formed depressions 7 therein, 5 and the upper or outer face of such sheet will have type elevations or printing portions 9 formed thereon which are faithful reproductions of the type faces of the original type body, the non-printing portions 8 10 between these type elevations or printing portions 9 of the sheet being swelled or curved by reason of the surface tension exercised on the metallic sheet, and the pressure exerted on the sheet against the supporting action of the individual type underlying the sheet, as will be understood by reference to my co-pending application filed May 20, 1916, Serial No. 98,906. Likewise, 15 that face of the phenolic sheet 6 which contacts with the metallic sheet 5 will have type depressions formed therein, by the type elevations of the metallic sheet. After the pressure has been exerted for a sufficient length of time to form the sheets as above 20 described, it is released, and the next step is to remove the imposed sheets 5 and 6 from the type body in the press.

I might here mention that if it is desired 25 to produce a flat matrix for making flat printing plates the sheets may be permitted to remain in the press until the phenolic sheet has set to hard, inflexible form, but if it is intended to make a curved matrix, for producing curved printing plates, then 30 the sheets are removed from the type body and press while the phenolic sheet still possesses a certain degree of flexibility or before it is completely set so that it may be bowed or bent to curved form, along with 35 the metal sheet as may be required, and as will be readily understood. When the two contacting sheets 5 and 6 are removed from the type body and press they are carried to a casting box 11, and clamped in proper position 40 therein, and a body of molten metal is poured therein and against the face of the metal sheet 5 having the type-formed depressions 7 therein, so that when cooled a soft metal backing 12 results which is faced 45 by the metal sheet 5, the type-portions 9 of which are intended to form printing or impression faces. The backing 12 may be a soft metal such as a lead alloy, or it may be aluminum or any other suitable substance. 50 Preferably the metal sheet 5, before being used is treated on the backing face by being chemically cleaned with a suitable chemical such as a soldering fluid, and while still moist from the cleaning chemical is coated 55 on this face with a thin layer of alcohol rosin solution which dries out to a thin film of rosin to prevent the greasing or soiling of the surface and the formation of oxids and to furnish a proper flux for the union 60 of the backing.

65

After the backing 12 has been applied by casting, the whole is removed from the box and the backing 12, is then trimmed or shaved, preferably while the metal sheet 5 is still in contact with the phenolic sheet. If 70 pressure is used in casting it may not be necessary to shave the back face of the soft metal backing 12. The phenolic sheet which of course lies at the opposite face of the metal sheet from the backing 12, may 75 now be stripped from the metal sheet, and we have a complete stereotype plate composed of a backing faced with a hard, close-grained metal sheet, which will in printing produce effects simulating electrotype work, 80 the plate itself closely resembling an electrotype in appearance. I also desire to call attention to the fact that when the phenolic sheet is stripped from the metal sheet, after the casting operation, it, of itself, constitutes 85 a matrix with type depressions and as such may be used in the production or duplication of other cast plates or printing faces. In other words, it provides a hard, durable rigid matrix or mold which may be used an indefinite number of times for the manufacture of duplicate plates or printing faces. In forming a plate with such a phenolic matrix I may employ a resilient 90 or plastic backing constituting a blanket or pressure surface against which pressure is exerted to force the metallic sheet or plate against the matrix.

When the metallic faced printing plate 95 herein described is completed the backing 12 will be firmly united to the facing plate 5 by the cohesion of the material of the backing with the indented surfaces of the contacting face of the plate.

In some instances it may be desirable to 100 make the matrix by impressing a phenolic sheet directly against the type body in the chase, and then using this matrix to make the metallic facing or printing sheet by 105 pressing the metal sheet against the phenolic 110 matrix with the aid of a resilient yieldable body such as a rubber blanket, or with a plastic material such as a fusible phenolic composition. The casting of the soft metal back on the metal sheet would be accomplished 115 in this instance just as above described.

While I have herein shown and described 120 one embodiment of my invention I wish it to be understood that I do not confine myself to all the details herein set forth by way of illustration, as modification and variation may be made without departing from the spirit of the invention or exceeding the scope of the appended claims.

125 What I claim is:

1. The herein described method of making a printing plate which comprises placing a facing sheet in contact with the printing face of a body of type, imposing a sec- 130

- ond sheet of moldable material on the facing sheet, subjecting the two sheets to pressure to impress the type faces in the facing sheet and to transfer such impression to the sec-
5 ond sheet, removing the two contacting sheets from the type body, and then depositing a backing body of soft material against the exposed face of the facing sheet while the latter is still in contact with the second sheet, said backing body being subsequently hardened to form a permanent backing for the facing sheet, and then stripping the facing sheet with its backing body from the second sheet.
10 2. The herein described method of making a printing plate which comprises placing a substantially homogeneous metallic facing sheet in contact with the printing face of a body of type, imposing a second sheet of
20 plastic material on the metallic sheet, subjecting the two sheets to heat and pressure to impress the type faces in the metallic sheet and to transfer such impression to the second sheet and substantially harden and
25 set the latter, removing the two contacting sheets from the type body and then depositing a body of molten metal against the exposed face of the metallic sheet while the latter is still in contact with the second sheet, said molten metal forming a metallic back-
30 ing for the said metallic facing sheet, and then stripping the second sheet from the metallic facing sheet.
3. The herein described method of making a printing plate which comprises placing a metallic facing sheet in contact with the printing face of a body of type, imposing a second sheet containing a phenolic condensation product on the metallic sheet, subjecting the two sheets to heat and pressure to im-
35 press the type faces in the metallic sheet and to transfer such impression to the second sheet and to substantially harden and set the latter, removing the two contacting sheets from the type body and then depositing a body of molten metal against the exposed face of the metallic sheet while the latter is still in contact with and supported on the second sheet, said molten metal forming a permanent metallic backing for said metallic 40 facing sheet, and then stripping the second sheet from the metallic facing sheet.
45

Signed at New York, in the county of New York and State of New York this 25th day of November, A. D. 1916.

EMIL E. NOVOTNY.
